CONNECTING STRIP

Pieter van Leeuwen, Hilversum, Netherlands, assignor, by mesne assignments, to North American Philips Company, Inc., New York, N. Y., a corporation of Delaware

Application December 3, 1953, Serial No. 396,017

Claims priority, application Netherlands December 5, 1952

8 Claims. (Cl. 317—112)

This invention relates to a connecting strip comprising a plurality of relatively insulated connecting members or contact members and more particularly to a structural element of a contact bank for automatic telephone systems or similar apparatus.

It is known to build up contact banks by stacking a plurality of connecting strips, each comprising a series of contact members which in most cases project on each side from the edge of the strip. As a rule, the ends at one side of the strip are intended for securing the multiple cables and those at the other side for co-operation with a movable contact member. The known connecting strips for this purpose are, in most cases, formed by clamping a series of contact members between insulating strips or, as is more usual, surrounding the series of contact members in a templet by casting or moulding with an insulating plastic material, which is subsequently hardened. The connecting strips thus obtained have the disadvantage that there are comparatively large tolerances as a result of the limited accuracy in working and inner action of the insulating material, such as contraction in cooling. Not only comparatively large tolerances in the spacing between the contact members of a strip are present but also deviations in the mutual positions of the contact series of a plurality of connecting strips assembled into a contact bank are unavoidable. A consequence of all this is that a contact bank for a selector switch for automatic telephone systems which comprises a determined number of contacts per layer is limited to a determined minimum size since it is necessary that the wipers shall co-operate in the correct manner with the contacts of the bank at each stop position of the wiper carrier of the selector. Therefore, as a result of the said tolerances, the spacing between the contact members cannot be so small as would be possible otherwise.

In the manufacture of known connecting strips comprising flat contact members use is commonly made of a series of contact members which are obtained in the correct mutual positions by punching a metal plate, and the extremities of which are connected to a remaining portion of the plate. After the said coherent series of contact members has been provided in the connecting strip, the positions of the plate connecting the extremities of the contact member are cut away. This method has the disadvantage that an important loss of material is involved.

The object of the invention is to provide a connecting strip comprising a plurality of relatively insulated contact members which strip can be manufactured with small tolerances and in which the loss of material in forming the contact members is very small. Owing to the small tolerances which also permit accurate stacking of a plurality of connecting strips according to the invention to form a contact bank, it is possible either to admit more contact members per series with a given size or to reduce the size of the strip when a determined number of contact members per series is re-

2

tained. This affords the advantage that in a contact bank for a selector built up from such strips more contacts can be wiped per unit time without increasing the mass forces which occur when the wiper carrier is accelerated or stopped. This is very important, more particularly, in systems for direct telephony, that is to say, telephone systems without registers.

According to the invention, the connecting strip is constituted by a metal supporting strip having a plurality of transverse grooves in which pieces of metal wire projecting from each side of the strip are centered in an insulating manner by means of at least one wire or ribbon of flexible insulating material, for example nylon cord, extending in the direction of the length of the supporting strip and under the successive pieces of wires, the pieces of wire and the insulating wire or ribbon, at their crossings, being inter-connected and connected to the supporting strip with the use of an insulating adhesive.

20 Since the supporting strip is of metal for which a light weight aluminium that may be anodized is preferred, it may be manufactured with very small tolerances. Furthermore, electric screening between the contact members of the various strips is ensured automatically in stacking a plurality of such connecting strips.

In order that the invention may be readily carried into effect, it will now be described in detail with reference to the accompanying drawing showing, by way of example, one embodiment thereof.

30 Fig. 1 is a plan view on a semi-circular connecting strip intended as a structural element for a contact bank of a rotary switch for automatic telephony.

Fig. 2 is a cross sectional view of this strip taken along the line II—II of Fig. 1.

35 Fig. 3 shows part of a longitudinal section taken along the line III—III of Fig. 1, and

Fig. 4 shows part of a longitudinal section taken along the line IV—IV of Fig. 1.

40 The embodiment shown in the figures comprises a flat aluminium supporting strip 1 which is semi-circular in shape. The strip 1 comprises, on its upper side, a plurality of transverse grooves 2, which are directed towards the center of the circle and in which contact members are provided in the form of pieces 3 of metal wire which project from each side of the strip.

45 For reasons which will be mentioned hereinafter, Fig. 1 shows three separate groups of pieces of wire, that is A, B and C, although the supporting strip 1 as shown actually comprises only pieces of wire such as those in group C.

50 The pieces of wire 3 are centered in an insulating manner in the transverse grooves 2 by the aid of two nylon cords 4 which extend in the direction of the length of strip 1 at a small distance from its edge. Said cords 55 extend under the successive pieces of wire 3 in order to pass on the upper side of the strip 1 to the subsequent transverse groove. An insulating adhesive 5 is provided for the mutual attachment of the pieces of wire 3 and the nylon cords 4 to the supporting strip 1 at the 60 crossing of a nylon cord and a piece of wire, that is to say in a groove 2 (see Fig. 4). Use is preferably made of an ethoxylen resin. The resin, after being provided, is cured in known manner, so that the pieces of wire 3 and the portions of the nylon cords 4 surrounding them 65 in part are extremely rigidly secured to the supporting strip 1. The nylon cords extend over the upper side of the supporting strip 1 in longitudinal grooves 6 in strip 1 having a depth smaller than that of the transverse grooves 2. Owing to the provision in the grooves 6, of the cords 4, the cords 4 do not project above the profile of the supporting strip 1. This is important,

since in stacking a plurality of such supporting strips the lower side of one supporting strip bears directly upon the upper side of the subsequent strip, so that the spacings between the series of pieces of wire in the connecting strips are determined only by the thickness of the metal supporting strips which can be obtained with very small tolerances.

The nylon cords 4, after having extended under all the wire pieces 3 in the supporting strip return through the said pieces of wire to their starting point, the returning part (4') also being secured at a crossing with a piece of wire with the use of the insulating adhesive.

For the sake of clearness, Figs. 2 and 3 show only a cross-section of the supporting strip 1, the pieces of wire 2 and the nylon cords 4 being omitted.

Not all of the contact members 3 provided in the supporting strip 1 are shown in Fig. 1. Those which are shown are divided into three groups A, B and C, which show the contact members 3 in different stages of working. As mentioned before, in the embodiment under consideration, all contact members provided in the supporting strip actually have the shape as shown for group C.

The contact members 3 of groups A are constituted by rectilinear pieces of metal wire having the same sectional area throughout their length.

The contact members of groups B are constituted by pieces of wire similar to those of group A, but with both ends flattened. Flat terminal parts 7 and 8 located in the same plane are thus obtained. The parts 7 and 8 may be formed before the pieces of wire are provided in the supporting strip, but a simpler method is first to provide pieces of wire similar to those of group A and then to flatten all the ends of the pieces of wire simultaneously in one operation.

The contact members in group C have acquired their ultimate shape by punching the flattened ends of pieces of wire (group B) secured in the supporting strip 1 to the desired size with the use of a cutting tool specially made for this purpose. The correct mutual positioning of the cutting tool and the connecting strip is obtained with the use of centering holes 11 provided in the extremities of supporting strip 1. During the punching operation those extremities of the pieces of wire which are located on the inner side of the strip are formed into more or less rectangular flat contact surfaces 10 which are accurately spaced apart and which are intended to be engaged by a wiper in a selector, the contact bank of which is built up from such connecting strips. The flattened ends 7 of the pieces of wire acquire by punching, as may be seen at 9, a profile which facilitates the securing of connecting wires thereto, for example, by soldering.

To ensure satisfactory contact between the contacts 10 and the cooperating wiper in a selector constituted by a plurality of the connecting strips described, it may be desirable that the contact surfaces should be provided with rare metal, for example palladium or silver. This may be effected by making those ends of the pieces of wire which, after being flattened, are punched into the desired shape of the contact surfaces 10, wholly or in part from precious metal, for example either by welding or securing in another manner a piece of precious metal wire to pieces of wire of base metal, for example of brass which are to be arranged in the transverse grooves 2 or by providing the relative ends of the pieces of wire beforehand with a precious metal.

In the embodiment described, the supporting strip 1 is semi-circular in shape, so that the connecting strip may serve as a structural element of a semi-cylindrical contact bank. However, the supporting strip may alternatively have a different shape, for example, it may be rectilinear and thus constitute a structural element for a rectilinear contact bank.

The connecting strip according to the invention may also be used for purposes other than as a structural element for a contact bank. Thus, it may be used, for example, as a distributing strip in telephone exchanges, as an assembling support for electric component parts in apparatus and as a connecting strip for the windings for energizing an electromagnetic relay. In relays the contact springs are in most cases clamped between insulating spacers mounted on a connecting strip secured to the yoke and comprise contact members for the energizing coils. Due to tolerances in the thickness of the connecting strip, the contact springs are not always correctly positioned relatively to the parts coupled to the armature and moving the contact springs, so that after-adjustment of the contact springs is necessary. This disadvantage is obviated when using the connecting strip according to the invention, the thickness of which is reproducible in manufacture with a high accuracy.

While I have shown and described the preferred embodiment of my invention, it will be understood that the latter may be embodied otherwise than as herein specifically illustrated or described and that in the illustrated embodiment certain changes in the details of construction and in the arrangement of parts may be made without departing from the underlying idea or principle of the invention within the scope of the appended claims.

What is claimed is:

30. 1. A combination of an elongated metal connecting strip being provided with a plurality of grooves therein positioned transverse to the direction of length of said strip, a relatively insulated piece of bare metal wire having a circular cross-section arranged in each of said grooves, at least one flexible, insulating member in each of said grooves, said member extending along a plane surface of said strip in the direction of length thereof and in said grooves and under said successive circular wires, and an insulating adhesive for connecting said circular wires and said insulating member at their points of engagement.
35. 2. A combination as set forth in claim 1 further comprising another groove extending in a direction parallel to the direction of length of said strip and having a depth smaller than that of said transverse grooves, and said insulating member being positioned in said other groove.
40. 3. A combination as set forth in claim 1 wherein said insulating member additionally engages a portion of the top surface of each of said wires and is secured at points of engagement therewith by said insulating adhesive.
45. 4. A combination as set forth in claim 1 further comprising two insulating wires, each extending adjacent to an edge of said connecting strip, and said insulating wires being adapted to center said wire pieces in said transverse grooves.
50. 5. A combination as set forth in claim 1 wherein said connecting strip is composed of aluminum.
55. 6. A combination as set forth in claim 1 wherein at least one end of each of said wires on the same side of said connecting strip is flattened.
60. 7. A combination as set forth in claim 1 wherein said insulating adhesive is an ethoxylene resin.
65. 8. A combination of an elongated metal connecting strip being provided with a plurality of grooves therein positioned transverse to the direction of length of said strip, a relatively insulated piece of bare metal wire having a circular cross-section arranged in each of said grooves, at least one flexible, insulating member in each of said grooves, said member extending along a plane surface of said strip in the direction of length thereof and in said grooves and under said successive circular

wires, an insulating adhesive for connecting said circular wires and said insulating member at their points of engagement, and one end of each of said wires consisting of a base metal provided with a surface of precious metal.
